PACKAGE FOR EXPLOSIVES

Floyd J. Rape, Edensburg, Pa., assignor to American Cyanamid & Chemical Corporation, New York, N. Y., a corporation of Delaware

Application May 27, 1937, Serial No. 145,023.

1 Claim. (Cl. 229—55)

My invention relates to improvements in explosives containers and particularly to those of the water-resisting type used for the packaging of blasting explosives.

5 The importance of suitable water-resisting containers for certain types of blasting explosives can be more readily understood if it is pointed out that quite often in blasting operations, conditions are encountered where the bore 10 holes contain appreciable amounts of water. Heretofore, where these conditions were encountered, it has been the practice to use a type of explosive primarily characterized by its water-resistant qualities. Since this type of explosive 15 is invariably of a gelatinous nature the producing of which is of relatively greater cost, and being further characterized by both their comparatively high densities and rates of detonation, it is therefore obvious that this type of explosive is 20 not always the best adapted for certain particular blasting operations and particularly those operations where a fine fragmentation of the material is undesirable.

Those skilled in the art are aware that the 25 oxygen balance of blasting explosives has an appreciable effect on their execution in that too great a deficiency in oxygen not only materially decreases their strength, but also materially increases the amount of poisonous gas liberated. 30 Since the explosive container enters into the explosive reaction and being to a greater or lesser extent deficient in oxygen it can be seen that its composition and weight have an appreciable effect on the execution of the explosive.

35 From the foregoing it can be seen that the ideal water-resistant explosive container is one that adds the least towards the oxygen deficiency of the explosive and yet among other things it should be able to withstand being submerged to 40 considerable depths of water without the permeation of water, nor should seasonal changes in the atmospheric temperature have any appreciable effect on its water-resistant quality. Furthermore, the cost of a water-resistant explosive 45 container should be such that its use in the packaging of adaptable types of explosives would be commercially practical.

I have found that a package made from sheets of material, preferably paper, laminated or bonded together by a joint consisting mainly of rubber and wax, meets all of the aforementioned 50 desirable characteristics of an explosive package.

The above bonding compound may consist of any of the so-called rubbers, such as pale crepe 55 rubber, smoke sheet rubber, gutta rubber, while

the waxes may include paraffine, beeswax, spermaceti, candelilla, carnauba, in say the proportions of from 6 to 30% of rubber to from 94 to 70% of wax with requisite quantities of an antioxidant. I prefer a composition comprising 5 approximately 15% of crepe rubber and 85% of paraffine wax compounded in the usual manner with a small amount of a suitable antioxidant.

One of the advantages flowing from the use of the above wax-rubber compound is that it does 10 not impregnate the reinforcing material or paper to which it is applied but, on the contrary, adheres to the surface thereof. Consequently, the surface of the paper opposite to that to which the material is applied is unaffected in its absorbent 15 properties. It is, therefore, entirely suitable to receive printed designations or it may have labels adhesively applied thereto.

One of the characteristics of the wax-rubber compound is its thermoplasticity. It may, therefore, 20 be bonded or laminated to the reinforcing material, such as paper, by the application of gentle heat and pressure and without the additional use of adhesives, nearly all of which have comparatively high oxygen deficiencies and are 25 more or less affected by seasonal changes in atmospheric temperatures.

This material is further characterized by its 30 unusual flexibility and when in film or sheet form may be stretched so that its length may be increased up to as much as 300% without rupture.

This material permits a much lighter weight 35 package being used, while still maintaining high water or moisture resistance. The laminating material is also particularly desirable in that it does not upset the oxygen balance of the combined explosive and container.

As an illustration of a specific form of wrapper made using the above material, reference may 40 be had to the accompanying drawings:

Fig. 1 is a sectional view of a sheet laminated according to this invention;

Fig. 2 is a perspective view of a tube made of 45 the laminated sheet of Fig. 1;

Fig. 3 is a fragmentary sectional view showing the side seam of the tube of Fig. 2;

Fig. 4 is a sectional view showing the method of sealing an open end of the tube of Fig. 4 to 50 make a package therefrom;

Fig. 5 is a perspective view showing a partially completed package;

Fig. 6 is a perspective view of a completed 55 package;

Fig. 7 is a sectional view of the package wall through the tie.

Referring now with particularity to the drawings, a composite wrapper may be made by laminating sheets 1 and 2 from paper or the like with an intermediate layer or film 3 of the above described rubber-wax composition. The three layers may be adhered together under the application of gentle heat and pressure which causes the thermoplastic layer 3 to soften, and upon solidification, the sheets 1 and 2 are adhered together. From this sheet, a tube 4 may be made having gussets in the side thereof, such as shown at 5, the overlapping edges being secured together as at 6 by means of a waterproof adhesive 7.

One end of the package may then be folded down against the body as at 8 using a suitable waterproof adhesive 9 having sufficient body to completely seal the folds. An asphaltum material is satisfactory for this purpose. The explosive may then be filled into the open ended package and the top of the body 10 folded and sealed similarly to the bottom end. Where desired, a tie 11 may be arranged around the body which will assist in holding the folded ends thereagainst.

Where desired, the entire completed package

with the contained explosive may be sprayed or painted with or dipped into a bath of moisture impervious material such as melted or liquid wax or the like which, upon solidification or evaporation, causes a closely adherent film 12 to exist over the entire package and gives added protection.

While the invention has been shown and described with particular reference to specific embodiments, yet it is to be understood that it is not to be restricted thereto, but is to be construed broadly and limited only by the scope of the claim.

I claim:

In a waterproof package adapted to contain an explosive, a container consisting of at least two sheets of material laminated with a layer of a moisture impervious substance therebetween, each end of said container being folded on itself and sealed against the entrance of moisture, in which the layer of moisture impervious material is a thermoplastic substance consisting mainly of rubber and wax and characterized by its ability to be stretched without rupture, said thermoplastic material being bonded to the two sheets of material making up the container.

FLOYD J. RAPE.
